US0D1043568S

(12) **United States Design Patent** (10) **Patent No.:** **US D1,043,568 S**
(45) **Date of Patent:** **** Sep. 24, 2024**

(54) **WIRELESS CHARGER**

(71) Applicant: **SHENZHEN FUTURE CHARGER TECHNOLOGY CO., LTD**, Shenzhen (CN)

(72) Inventors: **Wenzhong Wang**, Shenzhen (CN); **Yonghui Wei**, Shenzhen (CN)

(73) Assignee: **SHENZHEN FUTURE CHARGER TECHNOLOGY CO., LTD**, Shenzhen (CN)

(**) Term: **15 Years**

(21) Appl. No.: **29/865,150**

(22) Filed: **Jul. 11, 2022**

(51) LOC (14) Cl. **13-02**

(52) U.S. Cl.

USPC **D13/108**

(58) **Field of Classification Search**

USPC D13/103, 107, 108, 118, 119, 183, 184, D13/199; D14/432, 434, 439, 447, 251,

D14/252

CPC H02J 7/0044; H02J 7/0045; H04B 1/3877

(57) **CLAIM**

The ornamental design for a wireless charger, as shown and described.

DESCRIPTION

FIG. 1 is a perspective view of a wireless charger showing my design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings depict portions of the wireless charger in which the design is embodied that form no part of the claimed design.

1 Claim, 7 Drawing Sheets
